(57) **CLAIM**

The ornamental design for a safety helmet as shown and described.

DESCRIPTION

FIG. 1 is a front view of a safety helmet, according to the claimed design;

FIG. 2 is a rear view of the safety helmet of FIG. 1;
FIG. 3 is a left-side view of the safety helmet of FIG. 1;
FIG. 4 is a right-side view of the safety helmet of FIG. 1;
FIG. 5 is a top view of the safety helmet of FIG. 1;
FIG. 6 is a bottom view of the safety helmet of FIG. 1;
FIG. 7 is a perspective view of the safety helmet of FIG. 1;
and,
FIG. 8 is another perspective view of the safety helmet of FIG. 1.

The broken lines in the drawings depict portions of the safety helmet that form no part of the claimed design.
